UNITED STATES PATENT OFFICE.

MICHAEL HANT, OF APPLETON, WISCONSIN, ASSIGNOR TO EAGLE MANUFACTURING COMPANY, OF APPLETON, WISCONSIN.

BLOWER HOUSING OR FAN CASING.

Application filed January 13, 1926. Serial No. 80,919.

This invention relates to improvements in blower housings or fan casings.

It is the object of the invention to facilitate the construction of fan casings or the like by demountably holding the peripheral wall of such a casing under tension about the generally annular side walls thereof.

In the drawings:

10 Figure 1 is a side elevation of a device embodying this invention showing in dotted lines the position of the peripheral wall of the casing before being subjected to tension.

15 Figure 2 is a detail view taken in the section indicated at 2—2 in Figure 1.

Like parts are identified by the same reference characters throughout the several views.

20 The side walls 5 and 6 of the casing are generally annular in form, being provided at 7 and 8, respectively, with openings such as may be used either to receive shaft bearings or to provide inlets to the casing. Each such wall is provided with extensions at 9 forming the sides of a tangential outlet or discharge conduit.

25 The peripheral wall 10 of the housing extends continuously between its ends 11 and 12. It is made in the form of a flat strip except for marginal beads which provide centrally opening grooves 13 and outer radial flanges 14. Near the end 11 of the peripheral wall is a fitting 15 which is made fast to the wall by means of rivets 16 and receives tension members hereinafter to be described. The ends of the strip of metal which comprises fitting 15 are angularly bent or twisted as at 17 to lie substantially at right angles to the tension members.

40 Near its end 12 the peripheral wall 10 is acutely angled as at 18 to fit the angle between the arcuate peripheries of the end walls 5 and 6 and the rear margins 19 of the tangential extensions 9 of such walls.

45 In assembling the device the peripheral wall strip 10 is made to encircle the peripheries of the generally annular walls 5 and 6. The margins of walls 5 and 6 are received in the grooves 13. The ends 11 and 12 of the 50 peripheral wall extend upwardly along the opposite margins of extension members 9. When the peripheral wall is first applied it will be substantially in the position indicated by dotted lines in Figure 1. Thereupon tension members are used to draw the periph-

eral walls snugly into place about walls 5 and 6 to the full line position of the parts. In the present instance the tension members comprise the legs 20 and 21 of a U bolt, such legs being threaded and extended through suitable apertures in the twisted ends 17 of fitting 15 and there provided with nuts 22. The transverse member 23 of the U bolt extends across the device in the angle between the vertical and peripheral portions of wall 10 near the extremity 12 of such wall.

55 It will be obvious that by turning up the nuts 22 the peripheral wall may be drawn tightly into place to complete a blower housing which requires no rivets or other securing devices such as might make the structure semi-permanent in character. On the contrary, it is but the work of a few minutes to release nuts 22 and to disassemble the blower housing whenever it is desired to substitute a new blower fan therein or to obtain access to the interior thereof for any purpose.

60 While it is broadly immaterial just what direction is taken by the tension members 20 and 21 it is preferred that they should extend either tangentially to the arcuate peripheral portions of walls 5 and 6 or else that they should sub-divide the angle at 18.

I claim:

1. A blower housing comprising opposing end walls provided with extensions comprising opposing walls of an outlet passage, together with an encircling peripheral wall engaging the margins of said first mentioned 90 walls, and provided near its ends with tension members extending across said extensions and adapted to subject said peripheral wall to tension intermediate its ends.

2. As a new article of manufacture, a blower housing comprising a pair of opposed walls having substantially tangential extensions, in combination with a peripheral wall extending about the marginal portions of said opposed walls and extensions, a fitting applied to said peripheral wall near its outer end, a member extending transversely across said peripheral wall near its other end, and tension rods adjustably connecting said member with the ends of said fitting across the extensions of said first mentioned walls.

3. In a device of the character described, the combination with opposed wall members of generally annular contour provided integrally with tangentially extended portions,

of a peripheral wall encircling the margins of said members and extended outwardly along opposite margins of said portions near its ends, a fitting secured to said peripheral wall near its outer end, and a U bolt having a transverse portion engaging said peripheral wall near its inner end, the inner end of said peripheral wall being angled to provide a seat for said portion, the legs of said U bolt being received through the apertures of said fitting on opposite sides of the extended portions of said wall members and having nuts threaded thereon in engagement with said fitting, whereby adjustably to tension said peripheral wall.

4. In a device of the character described, the combination with opposed casing walls having corresponding arcuate margins, of a peripheral wall encircling said margins and provided with marginal grooves receiving margins of said opposing walls, together with a fitting connected with said peripheral wall near one of its ends, and a tension member connected with said peripheral wall near the other of its ends and adjustably bearing upon said fitting, said tension member being adapted to draw said peripheral wall snugly about the margins of said opposing walls and releasably to maintain all of said walls in rigid connection.

5. In a device of the character described, the combination with opposed walls provided with curved margins and corresponding extensions having their inside edges at an acute angle to portions of said margins and their outside edges substantially tangential to other portions of said margins; of a peripheral wall encircling said curved margins and having its ends extended up said edges, said peripheral wall having an acute angle near one end; means detachably interlocking said peripheral wall with said opposed walls; a transverse member seated in the acute angle of said wall; tension members connected therewith and traversing said extensions; and a fitting connected to said peripheral wall near its other end and adjustably connected with said tension members, whereby said members may be used to draw said peripheral wall about said curved margins releasably to maintain interlocking engagement between said peripheral and opposed walls.

6. In a device of the character described,

the combination with opposed walls provided with curved margins and corresponding extensions having their inside edges at an acute angle to portions of said margins and their outside edges substantially tangential to other portions of said margins; of a peripheral wall encircling said curved margins and having its ends extended up said edges, said peripheral wall having an acute angle near one end; means including beads substantially throughout the length of said peripheral wall engaging the margins of said opposed walls and detachably interlocking said peripheral wall with said opposed walls; a transverse member seated in the acute angle of said wall; tension members connected therewith and traversing said extensions; and a fitting connected to said peripheral wall near its other end and adjustably connected with said tension members, whereby said members may be used to draw said peripheral wall about said curved margins releasably to maintain interlocking engagement between said peripheral and opposed walls.

7. In a device of the character described, the combination with opposed walls provided with curved margins and corresponding extensions having their inside edges at an acute angle to portions of said margins and their outside edges substantially tangential to other portions of said margins; of a peripheral wall encircling said curved margins and having its ends extended up said edges, said peripheral wall having an acute angle near one end; means including beads substantially throughout the length of said peripheral wall engaging the margins of said opposed walls and detachably interlocking said peripheral wall with said opposed walls; a transverse member seated in the acute angle of said wall; tension members connected therewith and traversing said extensions; and a fitting connected to said peripheral wall near its other end and apertured to receive said tension members; together with thrust devices adjustably connected to said tension members and bearing on said fitting to draw said members through said apertures, whereby releasably to maintain interlocking engagement between said peripheral and opposed walls.

MICHIAEL HANF.
